(57) **CLAIM**

The ornamental design for a light control housing, substantially as shown and described.

DESCRIPTION

FIG. 1 is a front perspective view of the light control housing showing my new design wherein the broken line showing of the environment is for illustrative purposes only and forms no part of the claimed design;

FIG. 2 is a front elevation view thereof;

FIG. 3 is a rear elevation view with a circuit board thereof;

FIG. 4 is a rear perspective view of FIG. 1 with a heat sink wherein the circuit board is removed for showing portions of the design that are not shown in other views;

FIG. 5 is a rear elevation view of FIG. 4;

FIG. 6 is a top plan view of FIG. 4, the bottom view being a mirror image thereof; and,

FIG. 7 is a right side elevation view of FIG. 4, the left side being a mirror image.
